C. A. CAMPBELL,
INCANDESCENT GAS LAMP.
APPLICATION FILED AUG. 24, 1907.

2 SHEETS—SHEET 2.

UNITED STATES PATENT OFFICE.

CHARLES A. CAMPBELL, OF NEW YORK, N. Y.

INCANDESCENT GAS-LAMP.

No. 872,895.

Specification of Letters Patent.

Patented Dec. 8, 1907.

Application filed August 24, 1907. Serial No. 389,985.

To all whom it may concern:

Be it known that I, CHARLES A. CAMPBELL, of the city of New York, borough of Brooklyn, and State of New York, have invented certain new and useful Improvements in Incandescent Gas-Lamps; of which the following is a full, clear, and exact specification, such as will enable others skilled in the art to which it appertains to make and

10 use the same.

My invention relates to that type of incandescent gas lamps known commercially as "arclights" which are usually constructed in large sizes with metal "intensifiers" or 15 stacks and used for illuminating stores and other public places.

The object of my invention is to secure a strong and serviceable lamp which may be manufactured at an expense sufficiently low 20 to enable it to be placed on the market at a low price. I attain this end by peculiar features of construction concerning the frame parts and the combination of the chimney shade and gas tubes therewith.

25 It is also an object of the invention to improve the construction of the pilot light device and its arrangement with the chimney and intensifier, so as to reduce the liability to breakage and accidental extinguishment.

30 It is also an object of my invention so to organize the parts as to enable me to assemble the lamp in single or multiple units at will making either a single or cluster light as desired and also readily to convert the lamp 35 into an exposed or globe-inclosed light as desired. In this manner, by simple devices and operations, I provide a lamp which may be readily adapted to the various requirements of the trade.

40 The invention involves other features of importance and all will be fully set forth hereinafter and particularly pointed out in the claims.

Reference is had to the accompanying 45 drawings, which illustrate, as examples, two embodiments of my invention, in which drawings,

50 Figure 1 is an elevation of the lamp with parts in section, showing it assembled with a single burner; Fig. 2 is a similar view showing the lamp assembled with two burners and an inclosing globe; Fig. 3 is a sectional plan on the line 3—3 of Fig. 1; Fig. 4 is a sectional plan on the line 4—4 of Fig. 1; and 55 Fig. 5 is a detail section of the pilot light device.

Referring particularly to Fig. 1, 10 indicates the gas supply pipe which supports the upper shade 11, and from which two gas pipes 12 and 12^a branch. These pipes extend downward to a union 14 containing a valve 15 and sustaining the burner proper 16. Of the tubes 12 and 12^a the former leads the gas to the valve 15 while the latter is stopped off, in the adjustment shown in 60 Fig. 1, from the gas and serves simply to assist in sustaining the various parts of the lamp. Surmounting the burner 16 is a glass chimney 17 with a reduced upper end 17^a. This end 17^a is received within the lower end 70 of the metal intensifier tube 18 which extends upward between the tubes 12 and 12^a to a point near their upper ends and is covered by the usual cap 19. This tube 18 is held in position and the entire structure 75 braced by two brackets. Of these brackets the upper (see Fig. 3) is composed of two duplicate members 20, each having a semi-circular middle portion with radially disposed arms at its ends. The semi-circular middle 80 portions of the bracket sections match to embrace the tube 18 and the bracket is firmly yet adjustably fastened to the tube by a screw 21 or other fastening. The arms of the bracket sections oppose each other 85 in pairs and receive the tubes 12 and 12^a between them. These arms are pressed against the tubes by screws 22 or other fastenings. It will thus be seen that the arms of the bracket sections clamp the tubes 90 12 and 12^a while attachment of the bracket to the tube 18 is by means of direct contact of the screw 21 therewith. This secures firm and easy adjustment of the parts and avoids the expense of accurately constructed 95 parts.

The lower bracket (see Fig. 4) is composed of two sections 20^a similar to the sections 20 and having screws 21^a and 22^a similar to the parts 21 and 22 before described. 100 From each of the bracket sections 20^a radial arms 23 extend downward and outward and are fastened by screws 24 or like to an ornamental shade crown 25. These screws 24 serve also to support the 105 shade 29 by engagement with the usual flanged top thereof.

110 Adjacent to the lower end of the tube 18, the tube 12 has brazed, screwed or otherwise fastened thereto, a valve nipple 30 (see particularly Fig. 5) which communicates with the tube 12 and has a plug valve or cock 26

by which the gas movement through the nipple may be controlled with ease and accuracy. Rising from the nipple is a tube 27 and over this is snugly yet removably fitted the vertical arm of an elbow tube 28 which extends horizontally through a slot 18^a in the lower end of the tube 18. In the operation of the burner a small quantity of gas passes from the tube 28 and burns continually over the mantle of the burner so that the instant gas is turned on at the burner the same is automatically lighted. By arranging the pilot light at the end of the tube 18 the pilot light is protected by the shade 29 from drafts tending to extinguish the light and the shade may be raised or lowered at will to adjust the reflection of the light and the degree to which the pilot light is inclosed.

20 In assembling the lamp as a plural burner device, the intensifier is formed in two sections 18^b and 18^c of which the upper 18^b is of sheet metal tubing and the lower 18^c of cast metal in the form of an inverted Y, for 25 a double lamp and an inverted double Y for a quadruple lamp. The upper end of the section 18^c is received snugly within the lower end of the section 18^b and the reduced upper ends of the chimneys 17 are received 30 respectively within the lower ends of the branches of the section 18^c. The pilot light devices are carried respectively by the tubes 12 and 12^a and for this purpose the tube 12^a is opened to the flow of gas. The 35 lower ends of the branches of the section 18^c of the intensifier are orificed at 18^d to receive the pilot light devices as before described.

As shown in Figs. 1 and 2 from the valve 40 casing 14 a stud 31 depends and this is provided at its lower end (see Fig. 2) with a removable safety knob 32. 33, Fig. 2, indicates the burner inclosing globe which extends from a point within the shade 29 downward to the bases of the burner. This globe 45 33 is removably sustained by a band 34 fastened to its lower edge and having legs 35 joined at their lower ends to a collar 36 which fits removably on the stud 31 and is held in 50 place by a screw 37. To fit the globe 33 it is necessary to remove the knob 32 and replace the same after the collar 36 is secured. The knob then serves as a safety device to prevent the globe from falling should the screw 55 37 give way.

The construction and arrangement set forth produces a strong and serviceable lamp all of the parts of which may be cheaply constructed in dies and similar labor saving machines. By avoiding the necessity of accurately constructing the several parts the expense of manufacture is greatly reduced and by my improvements good results are secured without extreme accuracy of construction. And as will appear from the aforego-

ing description the lamp is susceptible to ready adjustment suiting it to the many varying conditions to be met with in the trade to which it relates.

Having thus described the invention, what I claim as new and desire to secure by Letters Patent of the United States is:—

1. An incandescent gas lamp having a burner, a glass chimney, a metal intensifier tube the lower end of which is engaged with the upper end of the chimney, side tubes extending down the sides of the chimney and intensifier, an upper bracket fastening the intensifier and side tubes, a bottom bracket also fastening the intensifier and side tubes, means projecting from the bottom bracket to sustain a shade, and a pilot light device carried by and communicating with one of the side tubes and extending through an opening in the lower portion of the intensifier. 85

2. An incandescent gas lamp having side tubes, an intensifier tube between them, a bracket loosely inclosing the intensifier, a fastening connected with the bracket and engaging the intensifier tube to fasten the bracket thereto and means for clamping the bracket to the side tubes. 90

3. An incandescent gas lamp having side tubes, an intensifier tube between them, a bracket loosely inclosing the intensifier, a fastening connected with the bracket and engaging the intensifier tube to fasten the bracket thereto, means for clamping the bracket to the side tubes and arms depending from the bracket to sustain the shade. 100

4. An incandescent gas lamp having side tubes, an intensifier tube between them, a bracket inclosing the intensifier, a fastening connected with the bracket and engaging the intensifier tube to fasten the bracket thereto, means for clamping the bracket to the side tubes, arms depending from the bracket, a shade crown and fastenings serving to secure both the shade crown and shade to said arms. 105

5. An incandescent gas lamp having side tubes, an intensifier tube between them, a bracket composed of duplicate members each having a semi-circular portion and projecting arms at its ends, the semi-circular portions embracing the intensifier tube and the arms 115 engaging the side tubes in pairs, means for holding the bracket members together and for clamping the said arms against the side tubes, and means for clamping the intensifier in the semi-circular portions of the bracket 120 members.

6. An incandescent gas lamp having side tubes, an intensifier tube between them, a bracket composed of duplicate members each having a semi-circular portion and projecting arms at its ends, the semi-circular portions embracing the intensifier tube and the arms 125 engaging the side tubes in pairs, means for holding the bracket members together and for clamping the said arms against the 130

side tubes, means for clamping the intensifier in the semi-circular portions of the bracket members and depending arms carried by the semi-circular portions of the bracket members to sustain the shade.

7. An incandescent gas lamp having a glass chimney an intensifier tube above the same, the end of one of said parts engaging the other and the intensifier having a slot in the lower end, a side tube, and a pilot light device carried thereby and projecting through the slot in the intensifier.

8. An incandescent gas lamp having a glass chimney an intensifier tube above the same, the end of one of said parts inclosing the other, and the intensifier having a slot in the lower end, a side tube, a pilot light device carried thereby and projecting through the slot in the intensifier, the pilot light device consisting of a valve, a tube projecting therefrom and an elbow tube loosely connected to the first tube.

9. An incandescent gas lamp having side tubes, an intensifier the lower part of which is branched, a bracket loosely inclosing the upper portion of the intensifier, a fastening connected with the bracket and engaging the intensifier to fasten the bracket thereto, means for clamping the bracket to the side tubes, a plurality of burners sustained below the intensifier, and burner chimneys respectively engaged at their upper ends with the lower ends of the branches of the intensifier.

10. An incandescent gas lamp having side tubes, an intensifier the lower part of which is branched, a bracket loosely inclosing the upper portion of the intensifier, a fastening connected with the bracket and engaging the intensifier to fasten the bracket thereto, means for clamping the bracket to the side tubes, a plurality of burners sustained below the intensifier and burner chimneys respectively engaged at their upper ends with the lower ends of the branches of the intensifier, the intensifier being constructed in two sec-

tions of which the upper is a single tube and the lower formed with the aforesaid branches.

11. An incandescent gas burner having side tubes, an intensifier, means fastening it between the side tubes, a burner sustained below the intensifier, a shade sustained above the burner, a stud below the burner, a globe adapted to inclose the burner and means for mounting the shade removably on the stud.

12. An incandescent gas burner having side tubes meeting at their lower ends, a burner sustained by the lower ends of the tubes, a shade sustained above the burner, a stud depending from the meeting ends of the side tubes, a globe adapted to inclose the burner below the shade and means for removably mounting the globe on the stud.

13. An incandescent gas burner having side tubes meeting at their lower ends, a burner sustained by the lower ends of the tubes, a shade sustained above the burner, a stud depending from the meeting ends of the side tubes, a globe adapted to inclose the burner below the shade, means for removably mounting the globe on the stud, comprising a band secured to the globe, legs depending from the band and a collar connected to the legs and removably secured to the stud.

14. An incandescent gas burner having side tubes meeting at their lower ends, a burner sustained by the lower ends of the tubes, a shade sustained above the burner, a stud depending from the meeting ends of the side tubes, a globe adapted to inclose the burner below the shade, means for removably mounting the globe on the stud, and a removable safety knob on the end of the stud for the purpose specified.
